UNITED STATES PATENT OFFICE.

WILLIAM LOWY AND JACOB MILCH, OF NEW YORK, N. Y.

PERFORATING MEANS FOR CYLINDER-PRESSES.

1,026,218.

Specification of Letters Patent.

Patented May 14, 1912.

Application filed January 20, 1911. Serial No. 603,767.

To all whom it may concern:

Be it known that we, WILLIAM LOWY and JACOB MILCH, both subjects of the Emperor of Austria-Hungary, the former residing at 5 New York, in the county of New York and State of New York, and the latter residing at Bronx, in the county of New York and State of New York, have invented certain new and useful Improvements in Perforating Means for Cylinder-Presses, of which the following is a specification.

The present invention relates to improvements in printing presses and particularly to the so-called cylinder-presses and has for 15 its object to provide a device, whereby the sheets to be printed upon may be perforated prior to printing.

With this object in view, our invention consists in the construction, arrangement 20 and combination of parts, which hereinafter will be fully specified.

In order to make our invention more clear, the same is illustrated in the accompanying drawing, in which similar reference letters 25 denote corresponding parts, and in which—

Figure 1 is an elevation of the printing cylinder, Fig. 2 an end view thereof and Figs. 3, 4, 5 and 6 are details of our improvement.

30 In the drawing, which forms a part of this specification, *a* denotes the printing cylinder, which is of ordinary construction and which is rotatively borne in the frame *b* of the machine. Secured to the ends of the 35 bar *c* which carries the hangers or guards *d* for the sheets, are blocks *e*, which by means of set screws *f* may be made adjustable. These blocks extend transversely toward the circumference of the printing cylinder and are formed with longitudinal 40 guide grooves *g*. Slidably guided in these grooves are vertically extending brackets *h* in which vertically adjustable bearing boxes *i* are arranged. The latter may be secured 45 in position by means of set screws *j*. The bearing boxes support a spindle *k* which extends longitudinally to the printing cylinder and parallel to the axis thereof. This spindle *k* is adapted to carry one or more perforators *l*, which may consist of a wheel 50 having sharp teeth and fixed between two side disks *m*, which by means of sleeves are adjustably fixed on the spindle *k*. The per-

forators are arranged transversely to the cylinder and adapted to perforate the sheets 55 on the printing portion *a'* of the cylinder while passing to the printing bed (not shown). The spindle carries at one end a gear *n*, which is adapted to mesh with the driving gear *o* of the printing cylinder. 60

Owing to the adjustability of the brackets *h* and spindle *k* respectively transversely to the cylinder, it is possible in case no perforation is desired, to cut out the perforators preventing their acting on the sheets. 65 The vertical movability of the spindle *k* in the brackets *h* enables the adjustment of the perforators in case of displacement of the sheets. Furthermore, the movability of the perforators along the spindle enables the adjustment of the perforators to the proper 70 place, at which the perforations are to appear.

As means for guarding the perforating wheels against vibrations in order to obtain 75 perforations on a straight line, the following device is provided: Secured below the bar *d*, which carries the brackets *h* and parallel thereto is a bar *p*, which is provided with a longitudinal groove *q*. Adjustably 80 secured to said grooved bar *p* by means of a pressure screw *r* is a vertically extending arm *s*, which has a longitudinal recess *t*. This recessed arm is adapted to be adjusted 85 in a position, in which the perforating wheel will engage into the recess of the arm and will thus during its operation be prevented from lateral vibrations. There may be several perforators and a corresponding number 90 of such guide arms.

We do not wish to restrict ourselves to the particular construction shown and described, since various modifications may be made without deviating from the principle 95 of our invention, but

What we claim and desire to secure by Letters Patent is:

In cylinder printing presses, the combination with the toothed printing cylinder, and the paper guard bar, of recessed blocks secured to the ends of said bar, vertical slotted brackets slidably borne in said blocks, bearing boxes vertically adjustable within said brackets, a spindle journaled in said bearing boxes, a gear on said spindle adapted to be 100 brought into meshing connection with the 105

teeth of said printing cylinder, longitudinally adjustable toothed disks on said spindle, said disks acting as perforators and adapted to perforate the paper prior to
5 printing, and horizontally adjustable slotted arms embracing said disks and serving as guards to prevent vibration of said perforators.

In testimony whereof we affix our signatures in presence of two witnesses.

WILLIAM LOWY.
JACOB MILCH.
